UNITED STATES PATENT OFFICE.

HARVEY C. STURDEVANT, OF JAMESTOWN, NEW YORK, ASSIGNOR TO THE STURDEVANT MACHINE CO., INC., OF JAMESTOWN, NEW YORK.

DOUBLE TRAVERSE FOR TEXTILE-MACHINES.

1,011,137.

Specification of Letters Patent.

Patented Dec. 5, 1911.

Application filed June 29, 1910. Serial No. 569,502

To all whom it may concern:

Be it known that I, HARVEY C. STURDEVANT, a citizen of the United States, residing at Jamestown, in the county of Chautauqua and State of New York, have invented a new and useful Double Traverse for Textile-Machines, of which the following is a specification.

This invention has reference to improvements in double traverse mechanism for textile machines and its object is to provide a means to prevent the strands in traveling across the roller and back dwelling at each side in the same place at the finish of each journey across the roller so that the tendency to cause excessive wear in these particular places is obviated thus doing away with the necessity of changing the worn rollers to perfect rollers to avoid bad work.

With the present invention the traverse motion as a whole follows a zig zag path so that the terminal points of the motion are constantly changing.

The present invention is particularly applicable for worsted spinning and is of markedly simple construction and is positive in action.

The invention will be best understood from a consideration of the following description taken in connection with the accompanying drawings forming a part of this specification, with the understanding however that the particular construction shown is susceptible of modification in various ways without departing from the salient features of the invention.

In the drawings:—Figure 1 is a view partly in diagram and partly in section showing the application of the invention.

Fig. 2 is a plan view of the traverse motion mechanism. Fig. 3 is a section on the line A—B of Fig. 4. Fig. 4 is an elevation of the double traverse motion mechanism as viewed from the left hand side of Fig. 1.

Fig. 5 is a view of a small portion of a drawing roll showing in dotted lines the path of the usual traverse motion. Fig. 6 is a diagram on an exaggerated scale illustrating the effect of the traverse motion illustrated in Fig. 5. Fig. 7 is a view of a small portion of a drawing roll showing the path of the strand under the action of the double traverse motion of the present invention.

Referring to the drawings there is shown

a back roller 1 in Fig. 1 mounted on a shaft 2, which shaft carries a worm 3 engaging a worm wheel 4 on one end of a shaft 5, the other end of which carries a heart cam 6 and also a worm 7 adjacent to the heart cam 6.

There is provided a main traverse bar 8 carrying a suitable number of roving guides 9 which direct the yarn to the rolls. The bar 8 has secured thereto a short rail 10 by a set screw 11 traversing a slot 12 in the rail which latter is provided for convenience of setting the double traverse mechanism in place. The rail 10 carries a stud 13 to which reference will hereinafter be made.

Mounted on the main traverse bar 8 is a box casting 14 having an opening 15 therein and this casting 14 carries at one side an arm 16 secured to the casting 14 by a set screw 17. The free end of the arm 16 is appropriately bent and carries a stud 18 entering the groove in the heart cam wheel 6.

Journalized in the casting or block 14 and extending through the opening 15 is a shaft 19 carrying within the opening 15 a cam sleeve 20 provided with a cam groove 21 receiving the pin 13 on the rail 10. The shaft 19 extends over the worm 7 on the shaft 5 and there carries a worm wheel 22 in mesh with the worm 7, while the other end of the shaft is journaled in a bracket 23 fast on the bar 8.

In Fig. 5 there is shown a small portion of the periphery of a roller 1 displayed and at 24 there is indicated schematically the path of the yarn caused by the traverse motion in ordinary use. At the finish of each journey across the roller there is a slight dwelling of the yarn always at the same distance from the circumferential center line of the periphery of the roller. The consequence of this is an excessive wear in these particular places as indicated in exaggerated form at 25 in Fig. 6, thus necessitating the changing of the roller to avoid bad work.

In accordance with the present invention the total lateral travel of the yarn is the same as in the traverses in general use, but the extent of each lateral movement of the traverse is less than in the traverses referred to, this being indicated in Fig. 7 which also illustrates the roller 1 in displayed condition, while the line of travel of the yarn on the roller is schematically indicated at 26. The lateral movement of the traverse may

be the same as before so far as the number of movements to the progress of the roller is concerned, but there is also provided a slower lateral movement which may be 5 timed with relation to the circumference of the roller so that the dwelling of the yarn at the end of the lateral journeys constantly changes with reference to the peripheral center line of the roller. There being no 10 point of excessive wear, an even surface is insured on the roller at all times.

Motion is imparted to the shaft 5 from the shaft 2 by way of the worm 3 and worm wheel 4 and rotary motion is imparted to the heart cam wheel 6 by this shaft 5. The heart wheel 6 imparts a reciprocatory movement to the block or casting 14 by way of the stud 18 and arm 16 and this motion is in turn imparted to the main traverse bar 8 by way of the rail 10 and stud 13 which latter engages in the cam groove 21 of the sleeve or enlargement 20 on the shaft 19, and this sleeve or enlargement 20 being housed in the opening 15 of the block 14 participates in the movement of the latter. So long as the shaft 19 is not rotating then the movement imparted to the traverse bar 8 will be agreeable to the movement imparted by the heart wheel 6 to the arm 16. A slow rotative movement is however imparted to the shaft 19 through the worm wheel 7 and worm gear or pinion 22, the rotative movement of the shaft 19 being slow as compared to the reciprocatory movement of the arm 16 and block 14. The relation of the block 14 to the traverse bar 8 is constantly changing because of the cam slot 21 in the sleeve or enlargement 20 causing a relative movement of the block 14 on the bar 8. Because of the rotative movement of the heart wheel 6 there is imparted to yarn passing through the roving guides 9 a sinuous movement with relation to the peripheries of the rollers to which the yarn strands pass, but because of the constantly changing relation of the block 14 to the traverse bar 8 due to the groove 21 there is another and slower traverse movement imparted to the yarn. There is therefore imparted to the yarn a primary traverse movement with relation to the surface of the roller over which the yarn passes combined with a secondary traverse movement of less frequency. By properly proportioning the parts recurrent points in the path of a yarn on a roller may be so infrequent as to have no effect upon the even wear of the roller. It will be observed that the cam or eccentric groove 21 causes the

second traverse movement positively in both directions.

60

What is claimed is:—

1. In a machine of the class described, a 65
slidable bar with guides thereon, a block
carried by said bar, a cam carried by the
block, operative connections between the
cam and bar, and actuating means for im-
parting reciprocatory movement to the
block and for actuating the cam carried by
said block.

2. In a machine of the class described, a 70
slidable guide carrying bar, a block on said
bar, a shaft journaled in the block and pro-
vided with a cam, an operative connection
between the bar and cam, means for rotat- 75
ing the cam, and means for imparting recip-
rocatory movement to the block.

3. In a machine of the class described, a
guide carrying slidable bar, a stud rail ad-
justable on said bar and provided with a
stud, a block on said bar, a cam in the block 80
engaging the stud on the rail, a shaft carry-
ing the cam, and means for rotating the
shaft and for imparting reciprocatory move-
ment to the block.

4. In a machine of the class described, a 85
slidable bar with guides thereon, a block
carried by said bar, actuating means for
imparting reciprocatory movement to the
block, connections between the block and
bar, and means controlling the said con- 90
nections for changing the relation of the
block and bar at a slower speed than the
speed of reciprocation of the block.

5. In a machine of the class described, a 95
reciprocatory guide bar, a reciprocatory
block thereon, operative connections be-
tween the block and bar, and means for
actuating said connections to vary the recip-
rocatory movements of the bar during the 100
reciprocations of the block.

6. In a machine of the class described, a
reciprocatory guide bar, a block slidably
arranged on said bar, means for reciprocating
said bar, a cam sleeve carried by said 105
block, and means on the bar coacting with
said cam sleeve for varying the reciprocatory
movement of the bar during the reciprocations
of the block.

In testimony that I claim the foregoing
as my own, I have hereto affixed my signa- 110
ture in the presence of two witnesses.
